UNITED STATES PATENT OFFICE.

JOSEPH H. BACON AND WILLIAM H. PAIGE, OF DETROIT, MICHIGAN.

STRAIGHT-WAY VALVE.

SPECIFICATION forming part of Letters Patent No. 281,228, dated July 17, 1883.

Application filed March 16, 1883. (No model.)

To all whom it may concern:

Be it known that we, JOSEPH H. BACON and WILLIAM H. PAIGE, of Detroit, county of Wayne, State of Michigan, have invented a new and useful Improvement in Straight-Way Valves; and we declare the following to be a full, clear, and exact description of the same, such as will enable others skilled in the art to which it pertains to make and use it, reference being had to the accompanying drawings, which form a part of this specification.

This invention relates to improvements in that class of straight-way valves wherein two valve-disks having wedge-shaped backs are forced to their seats by a plunger having a wedge-shaped end operating between the disks.

Our invention consists in the combination of two valve-plates wedge-shaped on their backs with a wedge-shaped plunger adapted to be reciprocated between the plates, and means for operating the plunger, the bearing-surfaces of the plunger being constructed on the arc of a circle, and the adjacent faces of the valve-plates being constructed to correspond therewith, whereby accurate adjustment of the valve-plates to their seats is obtained.

The invention is illustrated in the accompanying drawings, in which Figure 1 is a vertical central sectional view of a valve embodying our invention. Fig. 2, detached views of the plunger and the two valve-plates; and Fig. 3 is a horizontal sectional view through the valve-chamber, the valve-plates, and the plunger.

In the drawings, A represents the valve-chamber provided with suitable valve-seats, a and a' .

A' A'' represent the couplings.

B is the bonnet.

C and C' represent two valve-plates. These plates are constructed with wedge-shaped backs, being thicker at the bottom than at the top. They are also provided near the top with suitable lugs, c .

D is a wedge-shaped plunger, screw-tapped to receive the screw-cut valve-stem E, said valve-stem operated by a hand-wheel, E'. The wedge-shaped plunger is provided with suitable shoulders, d , adapted to engage with the lugs c upon the valve-plates, said shoulders constructed to allow the desired amount of play in the operation of the plunger before engaging with said plates. These valve-plates

being constructed in separate parts, as shown, may be readily located in position in the valve-chamber, as it is evident that by removing the bonnet and loosely engaging said plates about the plunger the whole may be dropped into their location, the plates resting upon suitable supports, a^2 and a^3 , in which position they will be forced upon the valve-seats by forcing down the wedge-shaped plunger by means of the screw-cut valve-stem.

It is obvious, since the valve-plates and the plunger are wedge-shaped, that by forcing down said plunger between the plates any desired pressure to force the valve-plates upon the valve-seats may be readily secured. It is also evident that by reversing the operation of the valve-stem the pressure of the plunger upon said plates will be relaxed as the plunger is drawn backward, and when the shoulders d of the plunger engage with the lugs e on the valve-plates, the valve-plates will be lifted and the valve-chamber will be opened.

The end of the plunger D, besides being wedge-shaped, has its two opposite bearing-surfaces constructed in the arc of a horizontal circle, and the adjacent faces of the valve-plates are provided with cavities corresponding to the form of the bearing-faces of the plunger, whereby an accurate adjustment of the valve-plates to the valve-seats is obtained.

The usual stuffing-box F and follower F', having a flange, f' , and the cap or nut G, are provided on the bonnet to make a tight joint for the valve-stem.

What we claim is—

In a straight-way valve, the combination of two plates, wedge-shaped on their backs, and having lugs c , a wedge-shaped plunger having shoulders d to engage said lugs c , adapted to be reciprocated between said plates, and mechanism for operating the plunger, the bearing-surfaces of said plunger being constructed in the arc of a circle, and the adjacent faces of the valve-plates being formed to correspond therewith, substantially as described.

In testimony whereof we sign this specification in the presence of two witnesses.

JOSEPH H. BACON.
WILLIAM H. PAIGE.
